SOUND RECORDING

William L. Woolf, Long Island, N. Y., assignor to
 Film Recording Corporation, a corporation of
 New York

Application May 15, 1936, Serial No. 80,010

2 Claims. (Cl. 274—38)

This invention relates to a method of producing a sound record on any suitable substance, usually plastics or metals, such as wax, phenolic resins, cellulose acetate, cellulose nitrate, and other cellulose compounds, aluminum, zinc, silver or gold, whether the substance be in the form of a cylinder, disc or strip.

More particularly it relates to recording sound impulses on a strip of film. The sound record may be made on the film in synchronism with a motion picture, or it may be made on the film without a picture or without any light sensitive emulsion as the emulsion plays no useful part in recording sound in accordance with my invention. One object of this invention is to produce a long time playing record in small, compact and convenient form. Another object is to produce a long time playing record at a low cost through permitting it to be widely used for many purposes, such as recording speeches, proceedings of conventions, meetings, court records, radio programs, telephone conversations, executive orders, legal documents, letters, dictation, etc.

I am fully aware that numerous attempts have been made to produce a satisfactory sound record on a ribbon, strip, or motion picture film. Some have tried recording with a heated stylus. Others have tried various means which soften or tend to soften the material of the strip for recording purposes. Some have tried recording with a sharp V shaped stylus which cuts into the material and removes a thin thread from the record groove. This method leaves the groove so rough that when the sound is reproduced the scratch level is unduly high. In order to overcome the scratch level, burnishing has been tried. This is the most successful method at the present time. By this method a conical shaped stylus is employed which terminates in a hemispherical shaped extremity. The rounded needle forces the material down and out, and compresses it, leaving the material of the groove imbedded in the film. This method polishes the groove and greatly diminishes the needle scratch. This method has inherent in it, however, two disadvantages, both of which tend to attenuate the recording of the high frequencies. First, is the comparatively heavy pressure required on the needle, and second is the comparatively large diameter of the needle, particularly the diameter parallel to the recording groove. The high pressure and large diameter tend to cause the material of the record to flow with a jelly-like motion so that on the high frequencies wherein the amplitude of vibration of the needle is very small, the amplitude in the recorded groove

is even less due to this flowing action of the material. The large diameter of an embossing needle also attenuates high frequencies because the needle destroys its own record when the diameter of the needle is not very small compared with the distance traversed by the film during the recording of a full wave.

I have found after extensive experimentation that I can, by properly shaping the point of the cutting stylus, obtain the high frequencies inherent in the sharp cutting needle, and the freedom from needle scratch associated with the burnishing needle. The shape of the cutting stylus will be most readily understood by assuming that I form it first as a cone with a hemispherical terminus, approximately two thousandths of an inch in diameter and that I then grind away slightly less than the front half of this needle, leaving a plain surface as the front face. This needle has sharp cutting edges and cuts away a portion of the material of the record. The rounded rear portion of the needle burnishes the path formed by cutting and leaves it smooth and comparatively free from needle scratch. The shape of this needle is shown by the accompanying drawing.

My invention is illustrated in the accompanying drawing in which:

Figure 1 is an enlarged fragmentary view showing the lower end of the needle in front elevation and in engagement with the film shown in section;

Figure 2 is an enlarged view like Figure 1 but showing the needle in side elevation; and

Figure 3 shows a short length of picture film with three sound grooves recorded in the usual sound track area.

Figure 4 is a sectional view taken along line 4—4 of Figure 2.

Figure 1 is a front view of the point of the needle greatly amplified engaging a film C. The line B—B is the contour of the needle while the line A—A represents the cutting edge. The line B—B represents the plane of widest dimension of the needle, that is, a plane coinciding with the axis of the needle. The axis of the needle is shown by the line D in Figures 1 and 2. The front surface or cutting face CF of the stylus may be flat, concave or slightly convex. The plane passing through the line A—A and bounded thereby is similar in shape, parallel to and slightly smaller than the plane passing through and bounded by the line B—B. The cutting edge A—A of the cutting face CF cuts away a portion of the material of the groove. The rounded por-

tion following the cutting plane A—A expands the groove and polishes its surface.

Figure 2 shows a side view of the needle greatly amplified. The thickness of the needle from front to back is approximately one-half that of the rounded needle, and the pressure on this type of needle can be very considerably less than that applied to rounded needles. Furthermore, the lateral movement of the needle during recording is accomplished with less pressure than that required with a round needle thus diminishing the flowing action of the record material. As indicated above, I prefer to form the point of the needle as a cone having a hemispherical or rounded terminus approximately two-thousandths of an inch in diameter. The front or cutting face of the needle is formed by grinding away slightly less than the front half of the cone, leaving a plane surface CF as a front or cutting face, as shown in Figure 2. The boundary of the cutting face is indicated by the line A—A in Figure 1. The curved surface located between the cutting face CF (plane A—A) and the central transverse plane B—B forms a burnishing surface bounding all parts of the edge of the cutting face CF. The separation between the cutting face CF and the central transverse plane B—B in Figure 4 has been exaggerated over the showing in Figure 2 for the purpose of more clearly showing the curvature of the burnishing surface. The distance between the two planes A—A and B—B will depend upon several factors including the character of the material of the sound record and also on the degree of burnishing desired. The greater the separation between these two planes, the greater will be the burnishing and vice versa. Accordingly, where it is desired to decrease the needle scratch, the distance between the two planes will be increased, but where it is desired to emphasize the high frequencies, this distance will be decreased. The included angle of the conical point will also depend upon several factors which may be easily determined, such as the weight carried by the needle and the

hardness of the material of the record. The cutting angle, that is, the angle which the axis of the needle bears to the surface of the record will also vary somewhat with different conditions, but in general it will be slightly inclined away from the right angular position as shown in Figure 2. The cutting point is preferably made of diamond, although needles made of sapphire or steel may be employed.

Figure 3 represents a sample piece of motion picture film showing three sound grooves E in the space usually occupied by one sound track.

As explained above, the separate sound grooves may represent three voice records all in different languages, or they may be identical sound recordings so that in the event of excessive wear in one groove, the other grooves may be used. I have also indicated above that for long-time playing records, the entire area of the film between the sprocket holes may be used for recording, and in order to have the film move continuously in one direction, it may be formed as an endless belt, or if desired, alternate sound grooves may be recorded and reproduced by running the film in opposite directions.

Having described my invention, what I desire to secure by Letters Patent is:

1. A recording stylus having a point conforming in shape to the larger part of a cone of rounded apex which has been cut along a plane parallel to and spaced from its longitudinal axis, whereby burnishing surfaces are provided surrounding the cutting face of the stylus.

2. A sound recording stylus, having a point formed of a substantially conical body portion having a substantially flat cutting face formed thereon substantially parallel to the axis of said conical body, said cutting face being displaced forward of said axis to provide burnishing surfaces bordering the sides of said cutting face, and said body portion being rounded at the terminus thereof.

WILLIAM L. WOOLF.
